UNITED STATES PATENT OFFICE.

SAMUEL RACHELMAN, OF ST. PAUL, MINNESOTA.

TROUSERS.

SPECIFICATION forming part of Letters Patent No. 511,797, dated January 2, 1894.

Application filed February 6, 1893. Serial No. 461,117. (No model.)

To all whom it may concern:

Be it known that I, SAMUEL RACHELMAN, of St. Paul, Ramsey county, Minnesota, have invented certain Improvements in Trousers, 5 of which the following is a specification.

My invention relates to improvements in trousers or overalls, and consists in the features of construction hereinafter particularly described and claimed.

10 In the accompanying drawings forming part of this specification, Figure 1 is a front elevation of a pair of trousers showing the inside of the back of the garment, and the fold and supporting straps. Fig. 2 is a rear elevation 15 of the same. Fig. 3 is a vertical section of the same taken on line $x-x$ of Fig. 1, and Fig. 4 is a plan view showing the form in which the material is cut for the rear portion of the trousers.

20 In the drawings the rear portion 2 of the garment, (see Fig. 4) is cut higher or longer than the finished garment, with rectangular notches 3 in the sides, the width of the notches being equal to the excess in length of the piece 25 over the finished garment. The intermediate or narrowed portion 5 is then folded upon itself to bring the edges 6 and 7 together to be stitched, as shown in Fig. 2, the ends 8 of the fold being stitched together as shown also in

30 Fig. 2. To the top of the inner fold 4, are se-

cured buttons 10 to which are attached elastic straps 11, the other ends of which are secured to buttons 12 upon the inner face of the band 13 of the trousers.

I claim—

35

1. As an improved article of manufacture, the trousers having the rear portion cut with rectangular notches in the edges thereof, the portion intermediate the notches being folded outward upon itself, and the meeting edges 40 of the notches stitched together, and the fold on the inside of the garment being connected by elastic straps to the waist band, substantially as described.

2. As an improved article of manufacture, 45 the trousers constructed with rectangular notches in the edges of the rear waist portion, the portion intermediate of the notches being folded outward and downward upon itself to form a double fold, the edges of the notches 50 being stitched together, and an elastic connection between the inner member of the fold and the waist band, substantially as described.

In testimony whereof I have hereunto set my hand this 26th day of January, 1893.

SAMUEL RACHELMAN.

In presence of—

H. S. JOHNSON,
T. D. MERWIN.
